LAUNDRY TAG

Angus F. Hanney, Norwood, Ohio, assignor to
The American Laundry Machinery Company,
Cincinnati, Ohio, a corporation of Ohio

Application August 16, 1932, Serial No. 629,033

5 Claims. (Cl. 40—23)

My invention relates to a laundry identification tag adapted to be applied to a piece of laundry goods for identifying the piece of goods as belonging to a particular lot or bundle throughout 5 various laundry operations.

The success of the identification tags depends upon the gripping power of the jaws and the effectiveness of a goods gripping means provided on the jaws, for example, a cooperating tongue and 10 groove. It is the object of my invention to provide an improved goods gripping means on the jaws of the identification tag which will effectively grip the goods in a manner to retain the tag on the goods against accidental removal or 15 displacement, and, at the same time, be of a nature to reduce possibility of goods tearing as caused by a pull on the tag and goods respectively, and of a nature such that there will be no holes pierced in the goods in securing the 20 tag to the goods.

Various other objects and advantageous features of my invention may be seen from the following description, and one embodiment thereof 25 may be seen in the accompanying drawing wherein similar characters of reference designate corresponding parts and wherein:

Fig. 1 is a perspective view showing a laundry identification tag embodying the features of my invention, the tag being shown prior to being 30 bent to gripping shape; Fig. 2 is a perspective view showing the tag as used for identifying laundry goods; Fig. 3 is a sectional view taken on the line 3—3 of Fig. 2; Fig. 4 is a view similar to Fig. 3 but showing a piece of goods disposed between and gripped by the jaws of the identification tag; and Fig. 5 is a fragmentary view showing 35 an identification tag holder on which a plurality of like tags may be disposed for assorting purposes, as will be hereinafter apparent.

The identification tag shown in the drawing 40 is of the type disclosed in the patent to Edwin Lane No. 1,621,259, for Laundry checking device, wherein each tag is one of a plurality of tags going to make up a distinct set and includes a single piece of resilient sheet metal 1 that is 45 bent to form substantially flat opposed jaws 2 and 3 and a spring portion 1', the jaws being adapted to receive laundry goods therebetween and being provided with sockets 4 for accommodating the nibs of a spreading tool whereby 50 goods may be inserted between and removed from between the jaws as, for example, pliers.

In suitable places, such as the face of one or 55 both of the jaws 2 and 3, an identifying number or legend 4' may be placed if desired and one

of the jaws, such as the jaw 3, has an integral lateral extension 5 which is provided with a warded opening 6 which fits over a key 7 having wards 8 that cooperate with the wardings in the slot 6. This warding principle or other slot 60 and key configuration provides for an unlimited number of sets of tags, each set being adapted to be disposed on a single key only whereby the tags and keys can be used for laundry assorting purposes. Likewise, it permits a like set of tags 65 to be assorted from a plurality of tags of different sets.

The success of the identification tags depends upon the gripping power of the jaws and the effectiveness of a goods gripping means provided on the jaws, for example, a cooperating tongue and groove.

In accordance with my invention, each of the jaws 2 and 3 is provided with fabric gripping tongues 9 and tongue receiving apertures 10, each tongue preferably having a top side of the same general configuration as the aperture which receives it. In this instance, the jaw 2 is provided with two aligned and spaced tongues 9 and one aperture 10 therebetween while the jaw 3 is provided with two aligned and spaced apertures 10 and one tongue 9 therebetween, whereby a tongue of one jaw cooperates with an aperture in the other jaw.

Referring to Figs. 1 to 4, it will be noted that 65 the tongues 9, formed by stamping or otherwise, as by the use of a sharp pointed tool or by casting, have rounded blunt end portions 11 and extend angularly and upwardly from the surface of the jaw in a direction away from the open end 99 of the tag, each of the tongues having an undercut 12 between the rounded blunt end thereof and the surface of the jaw on which the tongue is disposed on the side of the tongue that is toward the curved spring portion 1'. Likewise, 95 it will be noted that the apertures 10 are sufficiently large to permit entrance of the tongues thereto, with the rounded ends of the tongues being spaced a fairly short distance from one edge of the apertures.

In the use of this tag, the jaws 2 and 3 are spread apart by the insertion of the nibs of a spreading tool into the sockets 4 and operation of the spreading tool, and a piece of goods 14, see Fig. 4, is inserted between the jaws. Then, the 105 jaws are permitted to close under the influence of the bent spring portion 1' whereby the rounded blunt end 11 of each tongue 9 will enter and push the goods upwardly into the aperture 10 that cooperates with the tongue, the goods be- 110

ing forced into the undercut 12 of each tongue by the side of the aperture 10 adjacent the blunt rounded end 11 of the tongue, extending upwardly over the rounded end of the tongue and thence 5 outwardly between the free ends of the jaws 2 and 3.

With the above arrangement, three or more goods gripping points are provided with the use of a minimum number of tongues and apertures 10 and the cooperation between the blunt rounded end 11 of the tongue, the undercut portion 12 thereof, and the side of the aperture 10 adjacent the rounded blunt end of the tongue provides a lock between the goods and the tongue that will 15 effectively resist pulling the goods out of the tag without spreading the jaws thereof. For example, the tongues 9 extend upwardly and well into the apertures 10 and the goods 14 will have a holding pressure exerted thereon at a point 15 between the jaws as shown in Fig. 3, between the rounded blunt end of the tongue and the adjacent side of the aperture 10, and at a point 16 between the surfaces of the jaws 2 and 3. In addition to 20 this, the construction and arrangement of the tongues relative to the apertures 10 provide for a reverse bend in the goods as at 17, the goods extending from the free ends of the jaws 2 and 3, then being bent reversely in the jaws and then extending on back between the jaws towards the 25 bent spring portion 1'. It will be apparent that such construction and arrangement of the tongues and apertures will effectively prevent pulling the tags from the goods without first spreading the jaws and, at the same time, hold the tags on the goods without penetrating the 30 goods and with a minimum danger of the goods being torn by a pull on the tag or the goods.

What I claim is:

1. A laundry identification tag, comprising jaw members normally spring pressed toward one another and having free ends between which goods may be inserted, and goods engaging means on said jaw members including a tongue carried by one jaw member and an aperture in the other jaw member, said aperture being larger than said tongue and said tongue extending in a direction away from the free ends of said jaws, being undercut on the side away from said free ends, and having a rounded goods engaging end adapted to enter the aperture in said other jaw and to be disposed adjacent one side of said aperture when the tongue and aperture are in cooperative relation.

2. A laundry identification tag, comprising jaw members normally spring pressed toward one another and having free ends between which goods may be inserted, and goods engaging means on said jaw members including spaced tongues and an intermediate aperture carried by one of said jaws and spaced apertures and an intermediate tongue carried by the other of said jaws whereby tongues of one jaw cooperate with

apertures of the other, said apertures being larger than said tongues, and said tongues extending in a direction away from the free ends of said jaws, being undercut on the side away from the free ends, and having rounded goods engaging ends adapted to enter the apertures in said other jaws and to be disposed adjacent one side of said apertures when the tongues and apertures are in cooperative relation.

3. A laundry identification tag, comprising jaw members normally spring pressed toward one another and having free ends between which goods may be inserted, and goods engaging means on said jaw members including a tongue carried by one jaw and an aperture in the other for receiving said tongue, said aperture being larger than said tongue and said tongue including a top side extending upwardly and in a direction away from the free end of the jaw of which it forms a part to terminate in a rounded non-goods-piercing end, and having an under side cut back from said end to extend angularly downwardly toward the free end of the jaw and form a goods receiving space thereunder.

4. A laundry identification tag, comprising jaw members normally spring pressed toward one another and having free ends between which goods may be inserted, and goods engaging means on said jaw members including a tongue carried by one jaw and an aperture in the other for receiving said tongue, said aperture being larger than said tongue and said tongue including a top side extending upwardly and in a direction away from the free end of the jaw of which it forms a part to terminate in a rounded non-goods-piercing end, and having an under side cut back from said end to extend angularly downwardly toward the free end of the jaw and form a goods receiving space thereunder.

5. A laundry identification tag, comprising jaw members normally spring pressed toward one another and having free ends between which goods may be inserted, and goods engaging means on said jaw members including a tongue carried by one jaw and an aperture in the other for receiving said tongue, said aperture being larger than said tongue and said tongue including a top side of the same general configuration as said aperture and extending upwardly and in a direction away from the free end of the jaw of which it forms a part to terminate in a rounded non-goods-piercing end, and having an under side cut back from said end to extend angularly downwardly toward the free end of the jaw and form a goods receiving space thereunder.
